UNITED STATES PATENT OFFICE.

ETHAN I. DODDS, OF CENTRAL VALLEY, NEW YORK, ASSIGNOR TO FLANNERY BOLT COMPANY, OF PITTSBURGH, PENNSYLVANIA.

STAYBOLT STRUCTURE.

1,399,697.

Specification of Letters Patent.

Patented Dec. 6, 1921.

Application filed January 22, 1921. Serial No. 439,150.

To all whom it may concern:

Be it known that I, ETHAN I. DODDS, a citizen of the United States, and a resident of Central Valley, in the county of Orange 5 and State of New York, have invented certain new and useful Improvements in Stay-bolt Structures; and I do hereby declare the following to be a full, clear, and exact description of the invention, such as will enable others skilled in the art to which it 10 appertains to make and use the same.

This invention relates to improvements in staybolt structures, the object being to provide a construction wherein the bearing member, or the part that forms a seat for the head of the stay bolt, is locked in place 15 by the cap covering the bolt head, and it consists in the parts and combinations of parts as will be more fully explained and pointed 20 out in the claims.

In the accompanying drawings; Figure 1 is a view in section of one embodiment of my invention and Fig. 2 is a similar view of a modified form.

25 5 represents the outer sheet of the boiler, which in Fig. 1 is shown with an opening therein having a concave or curved wall, the curvature being in the arc of a circle to permit of the initial adjustment of the bolt bearing member 6. This bearing member 6 is circular in cross section and has a convex outer face conforming in curvature and size to the opening in sheet 5, and is open at its outer end and provided at its end with a 30 restricted opening 7 for the passage of the bolt 8 and also with an annular seat 10 around opening 7 on which the head 9 of the bolt 8 is seated.

The inner end of the bolt, (not shown) is 40 designed to be secured to the inner sheet of the boiler in the well known manner, and the bolt head 9 is provided with a slot 11 for the insertion of a tool for turning the bolt to screw the latter to the inner sheet.

45 With the construction thus far described, it will be seen that the bearing member 6 can be seated in the opening in boiler sheet 5, and the bolt 8 entered and secured to the inner sheet, the bearing member 6 being free 50 to turn and accommodate itself to the position or inclination of the bolt 8.

The hole 6 in the sheet 5 is counterbored as at 12 to receive the flange 13 on the cap 14, and the bearing member 6 is of such 55 depth and size as will permit of the initial

adjustment above referred to without having one edge or side thereof project above the seat 15 in the counterbore for flange 13, of the cap.

Located within the enlarged open end of 60 the bearing member 6 is the ring 16, the external diameter of which is slightly less than the internal diameter of the bearing member so as not to interfere with the normal movement of the latter. This ring is 65 provided with a plurality of depending fingers 17 the lower ends of which are provided with hook shaped end or catches 18 adapted to engage the inner surface of the sheet 5 and hold the ring against outward displacement, the fingers being of spring or bendable metal so that they will give to permit the parts to be assembled or disassembled. These fingers pass through openings 19 70 formed in the bearing member 6, which openings are of sufficient size as shown, to permit the bearing member 6 to move to accommodate itself to the position of the bolt. The inner face of the ring 16 is 75 threaded to engage an externally threaded portion 21 of the cap, so that when the cap is placed in position and connected with the ring, the cap will be held in place by the catches 18 engaging the inner face of the 80 boiler sheet 5.

85 Gaskets 22 are interposed between the flange 13 of the cap and the seat 15 of the boiler sheet 5, and also between the said flange and the tops of the bearing member 6 and ring 16 to prevent the escape of any 90 steam.

With this construction it will be seen that the bearing member 6 is loosely mounted in its seat in the boiler sheet 5, and can be initially adjusted to accommodate itself to 95 the position of the bolt 8, and is free to move slightly to compensate for unequal expansion or contraction of the inner and outer sheets after the cap has been secured in place. The cap is held in place by the ring 100 16 and is preferably flush with the outer surface of the boiler sheet 5 and is in a position to support the head of the bolt under a collapsing stress on the boiler sheets.

When the cap 14 is removed for the inspection of the bolt the ring 16 drops onto the seat 20 on the bearing member and is supported by the latter until again engaged and drawn outwardly by the cap, the screwing action of which pulls the ring outwardly 110

until the catches are in contact with the inner surface of the boiler sheet 5.

In the construction shown in Fig. 2 the bearing member 6^a is seated in a conical opening in the boiler sheet 5, consequently is not adjustable as in the construction previously described, and the flange 13 of the cap instead of resting in a counterbored seat in the boiler sheet, rests on the outer edge 10 of bearing member 6^a and on the top of ring 16^a.

The outer face of the ring 16^a, which is provided with fingers 17 having catches, as in the previous construction, is beveled as shown and bears against the inner beveled face of the bearing member 6^a and is limited in its downward movement by such contacting beveled faces. In this construction like that shown in Fig. 1, the attachment 20 of the flush screw cap to the ring locks the bearing member in place.

It is evident that many slight changes might be resorted to in the relative arrangement of parts shown and described without departing from the spirit and scope of my invention hence I would have it understood that I do not wish to confine myself to the exact construction and arrangement of parts shown and described but,

Having fully described my invention what I claim as new and desire to secure by Letters-Patent, is:—

1. In a staybolt structure, the combination of a boiler sheet having an opening therein for a bearing member, the latter having a seat for a stay bolt head, an internally threaded ring having catches passing through the bearing member to engage the inner face of the boiler sheet, and a cap having an externally threaded portion to engage the internal threads on the ring.

2. In a staybolt structure, the combination of a boiler sheet having an opening therein, a bearing member seated in said opening and having an internal seat for the head of a stay bolt, an internally threaded ring located within the upper end of said bearing member and provided with catches which pass through openings in the bearing member to engage the inner surface of the boiler sheet, and a cap having an externally threaded portion to engage the internal threads on the ring.

3. In a stay bolt structure, the combina-

tion of a bearing member adapted to be seated in an opening in the boiler sheet and provided internally with a seat for the head of a stay bolt, an internally threaded ring having catches passing through openings in said bearing member and adapted to engage the inner surface of the boiler sheet, and a cap having a peripheral flange to overlap said bearing member and provided with an externally threaded portion to engage the internal threads on the ring.

4. In a stay bolt structure, the combination of a bearing member having a curved outer face, a seat for a stay bolt head and a plurality of openings in its side, an internally threaded ring having catches adapted to pass through said openings in the bearing member, and a cap having a peripheral flange to overlap the upper end of the bearing member and an externally threaded part to engage the internal threads on the ring.

5. In a stay bolt structure, the combination of a bearing member having a curved outer surface; an internal seat for the head of a staybolt and a plurality of slots, an internally threaded ring within the upper open end of said bearing member and provided with catches adapted to project through the slots in the bearing member to engage the inner surface of the boiler sheet, and a cap having a peripheral flange to engage the outer face of the boiler sheet and with a depending externally threaded part to engage the internal threads on the ring.

6. In a staybolt structure, the combination of a boiler sheet having an opening therein a bearing member seated in opening and provided internally with a seat for a stay bolt head, an internally threaded ring having a plurality of hook shaped spring fingers the latter passing through openings in the bearing member and engaging the inner surface of the boiler sheet, and a cap having a peripheral flange to rest on said sheet and provided with an externally threaded member to engage the internal threads on the ring.

In testimony whereof, I have signed this specification in the presence of a subscribing witness.

ETHAN I. DODDS.

Witness:

EDWIN SPENCER RYCE.
